(57) **CLAIM**

We claim the ornamental design for a shotgun safe gun indicator, as shown and described.

DESCRIPTION

FIG. 1 is a perspective view of the shotgun safe gun indicator, showing our new design;

FIG. 2 is another perspective view thereof;

FIG. 3 is a left side plan view thereof;

FIG. 4 is a front plan view thereof; said rear plan view being a mirror image thereof;

FIG. 5 is a right side plan view thereof;

FIG. 6 is the top plan view thereof; and,

FIG. 7 is a bottom plan view thereof.
